UNITED STATES PATENT OFFICE.

EPRAIM MERAL TURNER, OF FORT WORTH, TEXAS.

TENT AND ATTACHMENT.

SPECIFICATION forming part of Letters Patent No. 415,826, dated November 26, 1889.

Application filed July 29, 1889. Serial No. 319,116. (No model.)

To all whom it may concern:

Be it known that I, EPRAIM MERAL TURNER, a citizen of the United States, residing at Fort Worth, in the county of Tarrant and State of Texas, have invented certain new and useful Improvements in Folding Tents; and I do hereby declare that the following is a full, clear, and exact description of the same, reference being had to the annexed drawings, making a part of this specification, and to the letters of reference marked thereon.

This invention relates to certain new and useful improvements in tents; and it has for its object to provide a tent-frame in such a manner that it may be readily folded into small compass, and which when extended for use will be very strong and serviceable.

The invention consists in the peculiar combinations and the construction, arrangement, and adaptation of parts, all as more fully hereinafter described, shown in the drawings, and then particularly pointed out in the appended claim.

The invention is clearly illustrated in the accompanying drawings, which, with the letters of reference marked thereon, form a part of this specification, and in which—

Figure 1 is a perspective view of my improved tent frame or support, shown in full lines as extended in position for use and in dotted lines as folded up ready for transportation or storage. Fig. 2 is a vertical cross-section through the head-block or cap. Fig. 3 is a perspective detail showing the connection between one of the rafters and its support.

Like letters of reference indicate like parts throughout the different views.

Referring now to the details of the drawings by letter, A designates a suitable head-block or cap, beneath the upper face of which are the recesses a, between the side walls of which the ends of the rafters are designed to be pivoted. These rafters are designated by the letter B and their pivots by the letter b. In the central portion of the cap is a hole c to receive the flag-staff or other like pole, which should be detachably inserted in said hole in any suitable manner to

provide for its removal when the tent is taken down.

The number of recesses a and of rafters B may be varied to suit the circumstances, four being shown in the drawings. The ends of the rafters, which are pivoted within the said recesses, are each formed upon two different angles, designated in the drawings by the letters d and e, the incline or angle e being such that when the rafters are extended it will have a broad bearing against the central portion or hub of the cap A, as shown at the left of Fig. 2, to relieve the pivot of strain, the outer face of said hub being slightly tapered, as shown, to assist in the accomplishment of this end, the longer incline d being provided for the purpose of preventing friction of the parts as the rafters are raised and lowered and avoiding sharp corners when the rafters are folded, as shown clearly in Fig. 2.

D are the supports or wall-poles, each of which is hinged to a rafter at the other end thereof by means of a hinge f, which is arranged upon the under side of the joint between the two parts and seated in a recess therein, as shown, so as to allow of the parts being folded closely one upon the other, so that the whole frame may be readily folded into the position in which it is indicated by dotted lines in Fig. 1. The ends of the supports or wall-poles are preferably sharpened to aid in their being driven into the ground. The ends of the rafters which are hinged to the wall-poles are cut upon such angles that when the parts are in their operative position, as shown in Fig. 3, the under side of the end of the rafter will have a flat bearing on the top of the pole and its vertical edge will be flush and in line with the edge of the pole, as shown in said Fig. 3.

E are brace or guy ropes attached to the wall-poles by means of screw-eyes or other suitable means and to stakes F, driven into the ground, as shown.

What I claim as new is—

The combination, with the cap A, having tapered central portion or hub and recesses

a, of the rafters pivoted in the walls of said recesses and having their ends formed with a short incline or bevel *e* and a longer and different incline or bevel *d*, substantially as shown and described, and for the purpose specified.

In testimony that I claim the above I have

hereunto subscribed my name in the presence of two witnesses.

EPRAIM MERAL TURNER.
